UNITED STATES PATENT OFFICE.

ELMER E. SMITH, OF GERING, NEBRASKA.

GATE LATCH.

Application filed March 12, 1923. Serial No. 624,536.

To whom it may concern:

Be it known that ELMER E. SMITH, a citizen of the United States, residing at Gering, in the county of Scotts Bluff and State of 5 Nebraska, has invented certain new and useful Improvements in Gate Latches; and he does hereby declare the following to be a full, clear, and exact description of the invention, such as will enable others skilled in 10 the art to which it appertains to make and use the same, reference being had to the accompanying drawings, and to the letters and figures of reference marked thereon, which form a part of this specification.

15 This invention relates to gate latches and has for an object to provide a latch which may be mounted upon and operate in combination with gates of substantially the ordinary construction and provide new and 20 improved features of convenience, economy and reliability. A further object of the invention is to provide, in combination with a gate panel swinging in either direction of a sliding latch bar an improved means of 25 sliding the bar to unlatching position, both by the use of the hand or the foot selectively. A further object of the invention is to provide, in combination with swinging gate panel of a sliding bar and a foot pedal adjacent the lower margin of the panel, having members extending yieldingly upon opposite sides of the panel to be engaged by the foot of the operator, the depression of which will slide the bar to unlatching position.

30 With these and other objects in view, the invention comprises certain novel parts, elements, units, combinations, functions and interactions as disclosed in the drawings, together with mechanical equivalents thereto, 35 as will be hereinafter more fully described and claimed.

In the drawings:

Figure 1 is a view in side elevation of a conventional gate with the improved gate 45 latch mounted thereon in operative and latched position.

Figure 2 is a fragmentary perspective view of the conventional gate panel, showing the gate latch in perspective.

50 Figure 3 is a sectional view taken on line 3-3 of Figure 1, showing in top plan the foot pedal arrangement.

Like characters of reference indicate corresponding parts throughout the several 55 views.

The improved gate latch which forms the

subject matter of this application is adapted to be associated with swinging gate panels of any usual and ordinary type, shown conventionally in the drawings and including 60 the gate bars, 10. This gate panel is hinged at 11 in the usual and ordinary manner to swing in either direction and a latch post 12, is properly spaced in relation thereto and carries a strike plate, 13.

65 For co-action with the strike plate, 13, a member 14 is mounted to slide longitudinally of the gate panel, a keeper, 15, being provided therefor, preferably rigidly connected with one of the members 10 and extending between the members 16 at the outer end of the panel, as indicated more particularly at Figure 2. This sliding bar 14 has an extremity 17 extending beyond the member 16 and in position for engagement with 70 the strike plate 13 in the usual well known manner.

75 For actuating the sliding bar, 14, a lever, 18, is pivoted to any convenient part of the gate, as one of the members 10, and pivoted 80 at 19 to the sliding bar 14. A spring 20 is appropriately mounted to hold the sliding bar normally yieldingly in position for interlocking with the strike plate 13. In the specific construction as shown this spring 20 is interposed between the keeper 15 and the 85 lever 18, but the invention is in no way limited to this specific construction. Also preferably the lever 18 will be contained by handles 21 extending upwardly in position to be 90 engaged upon either side of the gate so that the operator may oscillate the lever 18 when the gate is approached from either side.

95 From the lever 18 a cord or cable 22 extends through a keeper 23 which carries a roller, 24, for the purpose.

Slidable preferably vertically along one 100 of the members 16 is a rod 25, a keeper 26 being provided for permitting the sliding movement of the bar, such bar being connected with the cable 22 so that as the member 25 is moved slidably downwardly its action upon the cable 22 will be such as to move the lever 18 in the direction indicated by the arrow at Figure 2 to unlatch 105 the sliding bar 14.

110 Preferably integral with the member 25 are pedals 27 which are so formed as to be in position for ready access upon opposite sides of the panel, and sufficiently close to the ground for convenient actuation by the foot. To assist in the proper positioning

and sliding movement of these pedals and rod 25, said rod is continued by a loop or bend 28, embracing one of the members 16 and co-acting with the keeper 26 in the proper positioning and guiding of the pedal structure.

It is obvious that, as shown at Figure 1, the gate is latched by the usual and well known engagement of the extremity 17 with the strike plate 13. The gate being approached from either side for the purpose of opening the unlatching necessary may be accomplished either by depressing with the foot the pedal structure or engaging by the hand the levers 21, either action or both of which combined may be employed to move the lever 18 to dotted line position at Figure 1, throwing the latch bar also to dotted line position, which obviously will unlatch the extremity 17 and permit the swinging of the gate in either direction. The pedal or

lever being released the spring 20 serves to throw the bar 14 yieldingly to its outward limit and in proper position for interlocking with the strike plate 13, when the gate is 25 swung to closed position.

What I claim is:

The combination with a gate panel embodying spaced horizontal rails and vertical bars spaced upon opposite sides of one end of the rails, of a pedal member comprising an integral rod bent to present foot-engaging portions extending upon opposite sides of the panel with a connecting portion extending between one pair of rails, means 30 providing sliding engagement of the pedal member with both bars, a sliding latch, and means transmitting power from the pedal member to the latch.

In testimony whereof he hereunto affixes 40 his signature.

ELMER E. SMITH.
